UNITED STATES PATENT OFFICE

HUGO BRUNINGHAUS, OF FREMONT, OHIO, ASSIGNOR TO THE HENKEL-CLAUSS COMPANY, OF FREMONT, OHIO

MANICURING APPLIANCE

Application filed March 5, 1931. Serial No. 520,198.

My invention pertains to a manicuring appliance and more particularly to an article of the character named which possesses a plurality of cooperating features. While a plurality of distinct manicuring implements are included, some of which are adapted for individual use, it is believed that pairs of the implements have their functions complementarily successive instead of having their intended performances counteracting. Other pairs of features cooperate both structurally and functionally.

The object of my invention has been to design an appliance which would compactly, conveniently, economically, attractively and comfortably combine a plurality of manicuring implements. For realization of the comprehensive object just declared, my origination in this art, which is known to have become highly developed, includes; a hollow handle, the walls of which are impervious to moisture so as to be adapted to contain a liquid nail polish, one manicuring implement attached to one end of the handle, one manicuring implement attached to the side of the handle, an hermetical closure for the other open end of the handle and a pair of manicuring implements carried by opposite sides of the closure and one of which is adapted for useful insertion into the handle when the closure is in its functionating attached sealing position. Optionally, the relative location of some of the implements may be varied or one implement (for instance, a nail file) may be hingedly attached to the closed end of the handle so as to be adapted to be swung into a sheath provided in the handle.

It is to be realized that the scope of my invention comprehends many equivalent constructions. The showing of the drawings and the particular description are merely specific exemplifications of a plurality of mechanical embodiments and arrangements.

Adverting to the drawings:

Figure 1 is a view illustrating the preferred form of my invention.

Figure 2 is a view of the form shown in Figure 1 with certain parts in alternative position.

The preferred exemplification of my in-

vention, because embracing the most features, comprises a supporting member 1, which will exercise the auxiliary function of a handle. The member 1 is provided with a bore 2 open at one end and intended to contain a liquid nail polish. The member 1 in cheap embodiments of my invention may be of wood made impervious to moisture or the walls of the bore may be supplied with a coating effective as a seal for the polishing liquid. Better marketed forms of my invention may have the handle 1 composed of bakelite, or some other material suitable to color ornamentation. On one side the member 1 is fashioned with a lateral slot 3 extending along most of its length and intended alternately to serve as a sheath for occupancy by a nail file 4 having its one end hingedly attached at 5.

That side of the member 1, which is opposite to the side in which the slot 3 is formed, carries a skin covered buffer pad 6. A closure 7 is provided with screw threads 8 adapted for cooperation with complementary screw threads interiorly around the mouth of the bore 2. When the closure 7 is in its attached position, as shown in Figure 1, it effects a hermetical seal. Projecting beyond the threads 8 on the closure is an extension carrying a small brush 9 at its extremity. The brush is to be immersed in the polishing fluid when the closure 7 is in the position in which it appears in Figure 1 and is purposed to apply the nail polish to the exposed surface of a finger nail when the closure 7 is detached, as shown in Figure 2. The opposite end of the closure 7 is fashioned as a cuticle stick terminating as a beveled surface 10.

My invention is calculated to satisfy a popular demand for an emergency manicuring kit with all its implements of complementary function compactly assembled for the convenience of an owner carrying it in a vanity bag. Manifestly, it is a convenience to have eliminated the necessity of seeking four manicuring instruments from amongst the miscellaneous articles commonly collected in a vanity bag. It is to be understood that the size or shape of the imple-

ments of my appliance may be varied to suit future preferences. I furthermore record my realization that cuticle pushers made of wood cannot have the durability expected 5 from some harder molded material. The bore or cavity 2 might be enlarged at its open end either to increase its size or to lend a distinctive or ornamental feature.

I claim:

- 10 - 1. In an article of the character described, the combination of a handle fashioned with a cavity the walls of which are impervious to moisture, a manicuring implement carried by one end of said handle and a detachable closure for said cavity and carrying a brush adapted for positioning in said cavity when said closure is in its functioning position.
- 15 - 2. In an article of the character described, the combination of a handle fashioned with a cavity the walls of which are impervious to moisture, a detachable closure for said cavity and a pair of implements attached to the inner and outer sides respectively of said closure.
- 20 - 3. In an article of the character described, the combination of a molded receptacle impervious to moisture and adapted to serve as a handle, a water-tight closure for one end 30 of said receptacle, a brush connected to the inside of said closure and manicuring implements attached to the outside of said closure and to the other end of said receptacle respectively.
- 35 - 4. In an article of the character described, the combination of a receptacle impervious to moisture and adapted to serve as a handle, a water-tight closure for said receptacle, a brush connected to the inside of said closure 40 and differing manicuring implements attached to the outside of said closure to the other end and to one side of said receptacle respectively.

Signed by me, this 25th day of February,
45 1931.

HUGO BRUNINGHAUS.
